IRONING MACHINE

Filed Oct. 14, 1932

UNITED STATES PATENT OFFICE

2,011,388

IRONING MACHINE

Noble H. Watts, Bridgeport, Conn., assignor to
 General Electric Company, a corporation of
 New York

Application October 14, 1932, Serial No. 637,724

9 Claims. (Cl. 68—9)

The present invention relates to ironing machines and especially to ironing machines of the flat plate type wherein the ironing operation is performed by pressing a heated flat plate, termed 5 the shoe, against a padded flat plate, termed the buck.

The object of my invention is to provide an improved construction and arrangement in an ironing machine of this type and for a consideration of what I believe to be novel and my invention attention is directed to the following specification and the claims appended thereto.

In the drawing, Fig. 1 is a side elevation of an ironing machine embodying my invention; Fig. 2 is a top plan view thereof, the shoe being shown in one position in full lines and in another position in dotted lines; Fig. 3 is a perspective view partly in section of the operating means for the shoe; Fig. 4 is a detail sectional view taken on line 4—4 of Fig. 1, and Fig. 5 is a detail view of a modification.

Referring to the drawing, 1 indicates a base in the form of a flat plate which is preferably 25 triangular in shape, the forward end being of substantial width so as to provide a firm support. Projecting upwardly from the base is a tubular post or standard 2 which may be of any desired length. Mounted on tubular standard 30 2 is a sleeve 3 which carries an arm 4 on which is mounted a stationary buck 5. Buck 5 may have any suitable shape. Preferably it is rectangular, and, as is well understood, is suitably padded. It is the part of the ironer upon which 35 the cloth is spread by the operator preparatory to pressing or ironing. Sleeve 3 is fastened rigidly to tube 2 by means of one or more pins 6. Sleeve 3 terminates short of the top of tube 2 and mounted on the projecting upper end of the 40 tube is a collar 7 which is fastened to the tube by means of a set screw 8. The upper surface of collar 7 is flush with the upper end of tube 2 to form a shoulder and projecting upwardly from the shoulder is a central pivot post 9. In 45 the present instance, pivot post 9 is shown as comprising the upper end of a bolt having a head 10 seated against a shoulder on the inner surface and spaced from the upper end of tube 2. The pin or pins 6 pass through the bolt so 50 that it forms a rigid part of the standard. The posts so far described form a unitary structure which constitutes the stationary post of the machine.

Pivottally mounted on post 9 is an arm 11 which 55 is adapted to swing in a horizontal plane on the

post and which carries at its free end the shoe 12. Arm 11 is held in place by a nut 13 which screws onto the threaded end of pivot post 9. The free end of arm 11 is provided with a clevis 14 as shown particularly in Fig. 3 in which is pivoted a short bar 15 by means of a pin 16. The other end of bar 15 has formed integral with it a sleeve 17 which forms a support for the shoe 12.

Bar 15 is provided at its under side with a 10 projecting plate 18 located beneath arm 11 and provided with pivot pins 19 and 20, one located on each side of arm 11. Pivottally mounted at one end on pins 19 and 20 are flat rods 21 and 22 which extend parallel to each other and to 15 arm 11 and at their other ends are pivotally mounted on pins 23 and 24 (Fig. 4) located in slots in the sides of collar 1. The inner walls 25 and 26 of the slots form stops which are engaged by rods 21 and 22 to limit the parallel swing- 20 ing movement of arm 11.

With the above described arrangement it will be seen that when arm 11 is moved from the full line position shown in Fig. 2 to the dotted line position, rods 21 and 22 serve to turn bar 25 15 on its pivot 16 so as to give the shoe a substantially straight line motion relatively to buck 5.

At the lower end of sleeve 17 is an inturned flange 27 upon which rests the lower end of a coiled spring 28. Supported on the upper end 30 of coiled spring 28 is a post 29, the post being provided with a head 30 the under surface of which engages the spring. Post 29 is fastened to sleeve 17 by means of a key 31, the arrangement being such that the post will not turn relatively to sleeve 17 but can slide axially thereof guided by the key. Connected to the lower end of post 29 is a boss 32 which is attached to and forms a part of shoe 12, the shoe being fastened to the boss by suitable means such as the screws 32a, Fig. 2. Boss 32 is provided with a central opening 33 the lower end of which is closed by an adjustable plug 34 provided with a central opening through which the lower end of post 29 projects. Post 29 is provided with a suitable 40 shoulder with which plug 34 engages and against which it is held by a nut threaded onto the lower end of post 29. Plug 34 is cut away to provide a shoulder against which rests the lower end of a spring 35. Sleeve 17 is of less diameter than opening 33 and located in the annular space between the sleeve and the wall of the opening is a sliding bushing 36 the lower end of which engages the upper end of spring 35. Sleeve 17 is provided on opposite sides with trun- 50 55

nions 37 on which are pivoted cam plates 38 connected together at their rear ends by a frame 39, to the cross bar 40 of which is attached an operating handle 41. The forward ends of plates 38 are rounded to form cams or noses 42 which ride on the upper end of bushing 36. With this arrangement, when handle 41 is moved to turn frame 39 in a forward direction as viewed in Fig. 3, cam plates 38 are turned on trunnions 37, 5 forcing cams 42 downward on bushing 36, thereby moving the bushing downward on sleeve 17 and through spring 35 lowering the shoe 12. Sleeve 17 forms a guide in which post 29 slides vertically, the post being, in substance, a part of 10 shoe 12.

Mounted over the sleeve 17 and associated parts is a cylinder 43 which rests on boss 32. It forms a shield and cover for the enclosed parts and also gives a finished appearance to the structure. 15

In the use of the invention, the shoe is swung back to the dotted line position shown in Fig. 2 in which position it is to the rear of the buck leaving the buck unobstructed so that the cloth 20 to be pressed or ironed may be spread on the buck. Cam plates 38 occupy the Fig. 3 position, spring 28 holding the shoe in the raised position with bushing 36 in engagement with the lower flat sides of the cam plates. The shoe 25 stands parallel to the buck, being held in such parallel relation by the rods 21 and 22. The rearward swinging movement of the shoe is limited by rod 22 engaging the wall 26 on collar 7. After the cloth to be pressed or ironed is 30 spread on the buck the operator takes hold of handle 41 and pulls the shoe forward over the buck, the forward movement being limited by rod 21 striking surface 25 on collar 7. As shown in Fig. 2, handle 41 preferably curves forward 35 so as to be within ready reach of the operator. After the shoe is located over the buck, this being the position of the parts shown in Fig. 1, handle 41 is pressed downward, thereby turning cam plates 38 on trunnions 37 and causing cams 42 to slide on the upper end of bushing 36, forcing the bushing and shoe downward against the action of spring 28. Spring 35 is substantially stronger than spring 28 so that during the 40 initial movement the shoe moves downward without materially compressing spring 35. After the shoe engages the buck, further movement of the cams compresses spring 35, thereby pressing the shoe hard against the buck through the intermediary of spring 35. Spring 35 is adjusted for the desired degree of compression by means of 45 plug 34 which can be screwed a greater or lesser distance into boss 32. The handle 41 is pressed forward and downward until the points of cams 42 pass beyond the vertical, at which time a suitable stop means prevents further movement. 50 This stop means may comprise the handle 41 engaging the top edge of shield 43. With the points of the cams moved beyond the vertical, spring 35 will hold the shoe in pressed down position by reason of the stop preventing further movement of the cams. The operator may now leave the shoe in engagement with the buck 55 for the desired length of time to effect the ironing operation. After the ironing operation has been effected, handle 41 is raised to relieve the pressure on the shoe and permit spring 28 to return the shoe to its initial position as shown in Fig. 1 where it is out of contact with the buck. The shoe may then be swung back to its rearward 60 position as shown in dotted lines in Fig. 2.

When the shoe is swung back, it uncovers completely the buck so there is no danger of the operator coming in contact with the heated shoe while placing clothes upon the buck, and by causing the shoe to move in a straight line relatively to the buck, the shoe moves from over the buck with the minimum turning movement of the arm. The shoe may be heated in any suitable manner. For example, it may be electrically heated. By having handle 41 project forwardly it is brought 10 within convenient reach of the operator so that the operator can readily move the shoe back and forth and press it against the buck. This lends ease of operation to the ironer.

In Fig. 5, I have shown a modified form of 15 actuating mechanism for moving the shoe toward the buck. In this figure, 50 indicates a boss (corresponding to boss 32 of Fig. 1) which forms a part of the shoe. It is provided with a threaded neck 51 to which is attached the lower end of a 20 vertically extending tubular post 52. Post 52 fits into and is adapted to slide in a sleeve 53 which is carried by an arm 54 corresponding to bar 15 of Fig. 1. Post 52 is held normally in its uppermost position in sleeve 53, (this being the position 25 shown in Fig. 5) by a spring 55 which at one end engages an inturned flange 56 on post 52 and at its other end is fastened to the lower end of a stud 57 fixed to the head of sleeve 53. Post 52 is adapted to be moved downward in sleeve 53, thereby bringing the shoe into pressing engagement with the buck, by a cam 58 carried by a shaft 59 suitably pivoted in the walls of sleeve 53. Cam 58 bears against a roller 60 on the upper side 30 of sliding bushing or spring cup 61. Between the head of sliding bushing or spring cup 61 and the upper surface of boss 50 is a spring 62. Connected to the outer end of shaft 59 is an operating 35 handle 63. When operating handle 63 is turned in an anticlockwise direction as viewed from the 40 right hand side of Fig. 5, cam 58 moves downward, thereby forcing boss 50 and the shoe downward against the buck, pressure being applied through the intermediary of spring 62. Spring 62 is of a strength to give the desired pressing 45 force. After a predetermined force is applied, it will yield, thereby limiting the pressure between the shoe and the buck. The wall of tubular post 52 is provided with suitable slots 64 to permit of the described movement taking place. When 50 handle 63 is moved in the opposite direction, pressure on the shoe is released and spring 55 raises the shoe to its normal position. Spring 55 serves to keep roller 60 always in engagement with cam 58 during the return movement. 55 Spring 62 is a pre-stressed spring through which pressure is applied to the shoe. In other respects the construction indicated in Fig. 5 may be similar to that shown in Figs. 1 to 4 inclusive.

What I claim as new and desire to secure by 60 Letters Patent of the United States, is:

1. In an ironing machine, the combination of a buck, an arm one end of which is movable from a position over the central portion of the buck to a position away from the buck, a sleeve carried by the end of the arm, a shoe having a post, said post being slidably mounted in the sleeve, a first spring between the sleeve and post for holding the shoe in raised position away from the buck, a second spring, stronger than the first spring, and cam means for applying pressure to the shoe through the intermediary of the second spring to move the shoe towards the buck against the action of the first spring. 70

2. In an ironing machine, the combination of a buck, an arm one end of which is movable from a position over the central portion of the buck to a position away from the buck, a sleeve carried by the end of the arm, a shoe having a post, said post being slidably mounted in the sleeve, a first spring for holding the shoe in raised position away from the buck, a second spring, stronger than the first spring, and cam means pivoted on the sleeve for applying pressure to the shoe through the intermediary of the second spring to move the shoe towards the buck against the action of the first spring.
3. In an ironing machine, the combination of a buck, an arm one end of which is movable from a position over the central portion of the buck to a position away from the buck, a sleeve carried by the end of the arm, a shoe having a post, said post being slidably mounted in the sleeve, a first spring between the sleeve and post for holding the shoe in raised position away from the buck, a bushing slidably mounted on the sleeve, cam means for actuating the bushing, and a second spring, stronger than the first spring and located between the bushing and shoe, for transmitting the pressure applied to the bushing by the cam means to the shoe.
4. In an ironing machine, the combination of a buck, an arm one end of which is movable from a position over the central portion of the buck to a position away from the buck, a sleeve carried by the end of the arm, a shoe having a post, said post being slidably mounted in the sleeve, a first spring between the sleeve and post for holding the shoe in raised position away from the buck, a bushing slidably mounted on the sleeve, cam means pivoted on the sleeve for actuating the bushing, and a second spring, stronger than the first spring for transmitting the pressure applied to the bushing by the cam means to the shoe.
5. In an ironing machine, the combination of a buck, a support, an arm mounted on the support to swing in a horizontal plane, a pivoted extension on said arm, a shoe mounted on said extension and movable therewith into and out of position over the buck, a guide carried by the extension, a member carried by the shoe and arranged to move vertically with respect to the guide, restraining rods pivoted on said support and extension for moving the extension relative to the arm to prevent the rotation of the shoe relatively to the buck when the arm is swung, and means for moving the shoe relatively to the guide to bring it into engagement with the buck.
6. In an ironing machine, the combination of a buck, a support, an arm mounted on the support to swing in a horizontal plane, a pivoted extension on said arm, a shoe mounted on said extension and movable therewith into and out of position over the buck, a guide carried by the extension, a member carried by the shoe and arranged to move vertically with respect to the guide, restraining rods pivoted on said support and extension for moving the extension relative to the arm to prevent the rotation of the shoe relatively to the buck when the arm is swung, stops on the support cooperating with the restraining rods to limit the movement of the arm, and means for moving the shoe relatively to the guide to bring it into engagement with the buck.
7. In an ironing machine, the combination of a buck, an arm movable from a position over the buck to a position away from the buck, a sleeve carried by the arm, a shoe, a post carried by the shoe and slidably mounted in the sleeve, means including a cam pivoted on the sleeve for moving the shoe in one direction relatively to the sleeve to force the shoe against the buck, and a spring between the post and sleeve for moving the shoe in the opposite direction relatively to the sleeve to move the shoe away from the buck.
8. In an ironing machine, the combination of a buck, an arm movable from a position over the buck to a position away from the buck, a sleeve carried by the arm, a shoe, a post carried by the shoe and slidably mounted in the sleeve, means opposing movement of the post in a direction adapted to move the shoe towards the buck, a spring engaging the shoe, and means for applying pressure to the shoe through the intermediary of the spring to move the shoe towards the buck.
9. In an ironing machine, the combination of a buck, an arm movable from a position over the buck to a position away from the buck, a sleeve carried by the arm, a shoe, a post carried by the shoe and slidably mounted in the sleeve, a spring opposing movement of the post in a direction adapted to move the shoe towards the buck, a second spring, stronger than the first spring, and means for applying pressure to the shoe through the intermediary of the second spring to move the shoe towards the buck against the action of the first spring.

NOBLE H. WATTS.
